UNITED STATES PATENT OFFICE

RUEL ANDERSON JONES, OF COVINGTON, KENTUCKY, ASSIGNOR TO R. A. JONES & COMPANY, INC., OF COVINGTON, KENTUCKY, A CORPORATION OF KENTUCKY

SOAP PRESS

Application filed October 8, 1928. Serial No. 310,965.

This invention relates to improvements in die pressing machines for use in producing uniform cakes or bars of soap or any plastic material.

5 The general object of this invention is to provide a machine of this character which will rapidly and successively operate upon crude blocks of pliable material to accurately and neatly form or press the same into any 10 shape or with any desired embossing thereon or impressing therein.

Other objects of the invention relate to the co-ordinated mechanisms for automatically handling the bars or blocks of pliable material in successive order for performing the various functions thereon relative to delivery of the crude article to the pressing dies, operation of the pressing dies, and discharge therefrom, as ejecting the blocks from a magazine, conveying them successively to a point between forming dies, pressing them between the dies and expelling the pressed article therefrom through relative die movements, imparting a double pressure on each cake 25 for insuring a permanent formation and a glossy finished product, stripping the article from the respective dies, discharging it therefrom, and receiving and conveying the discharged finished product without damage thereto.

Further objects and advantages will be more fully set forth in a description of the accompanying drawings, forming a part of this specification, in which:

30 Figure 1 is a front elevation of the soap press of the present invention.

Figure 2 is a side elevation thereof.

Figure 3 is a sectional view taken on line 3—3, Figure 2.

40 Figure 4 is a sectional view taken on line 4—4, Figure 3, detailing the soap bar ejector and its operating mechanism, this view illustrating the ejector in its forward position where, combined with the movement of the carrier element, the mechanism has acted to transport a bar of soap to a position between the dies.

45 Figure 5 is a detail sectional view taken on line 5—5, Figure 3, detailing the carrier mechanism cooperating with the ejector

mechanism and showing the mechanisms in the same operative position as Figure 4.

Figure 6 is a detail view illustrating the mechanism for revolving the lower die to eject the soap, this view showing the parts 55 in position corresponding with Figure 4.

Figure 7 is a detail sectional view taken on line 7—7, Figure 3, showing the levers and actuating means for stripping or ejecting the pressed soap from the upper die, this 60 view corresponding in relative position of mechanism with Figure 4.

Figure 8 is a side elevation of the machine looking at the opposite side from Figure 2, the forward upper portion of the frame being broken away to illustrate the upper die frame or carrier actuating means, this view showing the toggle mechanism of the machine passing dead center in first soap pressing position.

70 Figure 9 is an enlarged fragmentary sectional view taken centrally of the dies and the upper die frame, illustrating the stripper mechanism therein, this view showing the upper die starting up after the pressing operation and the inner element being held stationary for stripping the soap therefrom.

Figure 10 is a sectional view taken similar to Figure 7, but showing the stripper mechanism in stripping position.

80 Figure 11 is a detailed fragmentary view of the machine, showing the upper die returned and the lower die reciprocated for discharging the pressed soap, this view also detailing the means operating the lower die soap ejector.

Figure 12 is a detail sectional view taken on line 12—12, Figure 1, illustrating the construction of the base end of the magazine.

Figure 13 is a sectional view taken on line 13—13, Figure 3, detailing the power transmission to the cross shaft.

Figure 14 is a sectional view taken on line 14—14, Figure 9, further detailing the lower die.

95 Figure 15 is a longitudinal sectional view and an end elevation of the resilient soap gripping element mounted on the end of the carrier rod.

Figure 16 is a sectional view taken on line 16—16, Figure 1, illustrating the construction of the base end of the magazine.

16—16, Figure 10, detailing the adjustable features of the stripper mechanism operating cam.

Figure 17 is a fragmentary rear view of a portion of the cam, showing the adjustable connection of the cam sections.

Figure 18 is a sectional view taken on line 18—18, Figure 8, detailing the slideable mounting of the upper die carrier on the frame.

Referring to the drawings, a hollow frame 20 is provided, this frame being provided with feet 21 extending out from the respective sides thereof and with a longitudinal groove or depression 22 parallel with the feet as a clearance for the use of lifting tools in moving the machine. A main power shaft 23 is disposed toward the rear of the frame traversing and journaled in the respective side walls 24—24 thereof.

A driving pulley 25 is mounted on one extending end of the drive shaft and a clutch mechanism indicated generally at 26 is disposed adjacent and within the pulley, co-operating therewith for coupling up the pulley to the drive shaft.

The reciprocating clutch element 27 for actuating the clutch lever 28 has a groove 29 therein at its outer end, this groove being entered at diametrically opposite points by shifter lever pins 30 formed in the respective arms of a yoke element 31 attached to the lower end of a fulcrumed shift lever 32 pivoted to the frame by means of a bracket 33 bolted to the side of the frame. A connecting rod 34 passes through the frame and has one end secured to the upper end of the fulcrumed shifter lever 32 and the other end pivotally attached to the upper end of a second fulcrumed shifter lever 35 on the opposite side of the machine, the second lever being the manually grasped lever for power control and being pivoted on a bracket 36 attached to the frame.

A second shaft 37 as a drive continuation is mounted at right angles to the first power shaft and above the same and within the frame. The shafts are in connection therewith through a spiral gear 38 on the main driving shaft engaging a companion gear 39 on the cross drive shaft 37 (see Figure 13). The cross shaft is journaled in the rear wall of the frame in a bearing 40 and at its forward end in the inwardly extending arm of a bearing bracket 41. From these driving shafts the power distribution to the various elements making up the movements of the machine will be described in the order of their operation on the work.

Going from the drive source to the work article intake for the machine, a magazine disposed at the front of the machine is generally indicated at 42. The magazine 42 is formed to receive cylindrical lengths 43 of plastic material, such as soap in its crude form. The

base element 44 of the magazine is supported on a bracket 45 and presents an inclined surface terminating in a straight vertical base end for the magazine. The wall forming this surface is reinforced by a centrally forwardly disposed rib 46, and a horizontally disposed attaching flange 47 is provided having slots 48 traversed by attaching screws 48^a entering into the support bracket. This provides for adjustment of the base element relative to a rear wall hereinafter described.

Toward the upper end of the inclined magazine wall of the base, the wall is notched out at each side as at 49, and downwardly extending attaching flanges 50 are provided adjacent each notched portion. A pair of angle iron strips 51 extend upwardly at the same angle as the base, being attached to the respective flanges 50 thereof, the top flanges of these angle iron strips being disposed in the same plane as the magazine wall of the base providing a flush surface therewith. A finish plate 52 of the same width as the base element extends substantially from the lower end thereof to the outer ends of the respective angle iron strips spanning the space between the angle irons and forming the magazine inclined support surface.

Side guides 53 for the cakes of soap are secured to the bottom of the magazine thus formed and are adjustably spaced apart the necessary distance for a free guided passage or movement of the cakes of soap downwardly therebetween.

The lower end of the magazine or chute, as it may be termed, is provided by the attachment of an angle iron piece 54 against the straight surface of the base element, the upwardly extending flange of the piece 54 being countersunk relative to the straight surface and to the finish strip (see Figure 12) so as to provide a flush surface therewith and the other flange forming the bottom.

The adjustment of the side rails is accomplished by having one of the side rails (see Figure 3) provided with an angle iron side piece 55 carrying a guide 53 and having slots 55^a therein disposed at right angles to the length of the magazine traversed by screws 56 passing through the magazine base and clamped thereto by means of wing nuts 57.

The lower end of the magazine is provided with a rear wall, this wall comprising, a length of flat plate 59 adjustably secured to the side of the frame by means of an angled piece or bracket 60. The rear wall is further built up by means of a second element 61 of flat plate riveted to the first piece and extending toward the discharge side of the magazine base and having a right angle flange 62 countersunk in the base angle.

The main rear wall of the magazine is spaced from the forward wall a slightly greater distance than the diameter of the bars

of soap providing a smooth sliding fit for the bars at its lower end and inclined forwardly in the same direction at a slightly less angle, thus providing a sort of hopper arrangement at the magazine base.

The discharge of the cylindrical bars is laterally of the magazine. The lowermost cake of soap is ejected from the magazine by a combined pushing and carrying operation. The mechanism for accomplishing this operation is as follows:

The cross drive shaft has a gear 63 secured at its forwardly extending end, this gear being in mesh with an idler gear 64 journalled in the bearing bracket 41 and the idler gear being in mesh with a gear 65 pinned to a cam shaft 66 disposed parallel to the cross shaft and exterior of the machine frame. The cam shaft is journalled at one end in the before described bearing bracket 41 and in the other end in a journal bracket 67 secured to the forward end of the frame. A closed cam element 68 is pinned to this shaft toward its forward end and operates a feed plunger actuating lever 69 by means of a roller 70 disposed intermediate of said lever and engaged in the cam track, the lever being pivoted at its lower end on a pivot bracket 71 bolted to the frame.

A guide frame 72 is bolted to the side frame immediately above the cam 68 and provides a horizontally disposed dovetail guideway 73 laterally disposed from the main body of the element. A reciprocating feed plunger or ejector 74 is bolted at its outer end to a slide 75 held in the guideway by means of a gib plate 75^a, the slide having a downwardly extending lug 76 connected to the upper end of the cam operated lever 69 by means of a link 77, providing a double pivotal connection. By this arrangement of cam, lever, and slide, the inner end of the plunger is adapted to engage the lowermost bar of soap shown at 78 and to slide the same laterally out of the bottom of the magazine.

A gripping element 79 is secured at the inner end of the plunger for engagement with the end of the bar of soap, this element being in the nature of a headed screw concentrically disposed relative to the plunger and held in place by means of a lock nut 80. The face of the head is provided with a radially disposed series of teeth 81 adapted to engage into the end of the pliable soap cake. The soap is presented to the machine in a pliable condition so as not to crumple or chip when it is acted upon by the teeth and the dies.

As the lowermost cake of soap is ejected the next bar rests on the top of the plunger and as the plunger recedes, the cake drops down into rest position on the base plate of the magazine in alignment for the next discharge.

Cooperating with the before described plunger is a reciprocating carrier element 82

adapted to engage the opposite end of the soap for the purpose of carrying it, after it leaves the base of the magazine, into a position relative to the pressing dies. A carrier element operating cam 83 is secured on the cam shaft 66 adjacent the first cam 68 and actuates a swinging lever 84 pivoted on a conveyor driving shaft 85 (hereinafter described). The cam groove engages a roller 86 on this lever and the swinging end of the lever is connected to one end of a fulcrumed lever 87 on the opposite side of the machine by means of a rod 88 extending through the machine.

The fulcrumed lever is mounted on a stud shaft 89 extending from a slide frame 90 secured to the side of the machine. The reciprocating carrier 82 is horizontally slideably mounted in the frame and in alignment with the ejector plunger and with the center of the cylindrical bar of soap.

The upper end of the fulcrumed lever 87 is connected to the slideably mounted carrier 82 by means of an adjustable link 92 pivotally attached to a bracket 93 pinned to the rod-like carrier 91 and to the upper end of the fulcrumed lever. The connection elements from the fulcrum lever to the carrier have free movement between a pair of bosses 94 slideably traversed by the carrier.

The device 95 secured to the inner end of the carrier for engaging the soap is detailed in Figure 15. The device 95 is in the nature of a compressible head resiliently engaging the end of the bar of soap and comprises a headed sleeve element providing teeth 97 after the manner of the engaging element on the ejector and a spring 98 under compression between an internally formed shoulder 99 within the sleeve and a collar 100 held against a pin 101 traversing the carrier rod and traversing slots 102 in the outer end of the sleeve.

The headed sleeve is thus adapted to be translated relative to the carrier rod, the length of the traversed slots against the compression of the spring so that the engagement of the carrier rod with the bar of soap is not a direct positive engagement but rather a resilient engagement through the compressible sleeve, this provision being made to prevent damage to the soap which might result if the movements were slightly out of adjustment or in case of overthrow.

The respective cams of the ejector plunger and the carrier are formed to time the movements of these elements to achieve the following result:

The ejector plunger engages the lowermost bar, shoves it outwardly and as its opposite end is emerging laterally from the magazine, the carrier element comes up into engagement therewith and then moves rearwardly at that moment and at the same speed as the ejector. Thus the pushing action of the ejec-

tor is converted into a carrier action in combination with the carrier rod and the soap is supported and transported between these tooth-faced feed elements to a point relative to the forming dies and there released at the moment the dies are brought together. The release is accomplished by continuing movement of the carrier rod 82 after the relative action of these soap bar carrying members has brought the bar into position over the forming dies. This continuing movement is sufficient to withdraw the teeth of the gripper elements from the bar of soap, (see dotted lines in Figure 5) whereupon the upper die descends upon the soap as the ejector moves back.

The movements for operating the dies to press the soap are of the following nature:

A means is provided for moving the upper die 105 downwardly into pressing engagement with the lower die 106, the lower die being stationary during the pressing operation. Another movement is provided operating in synchronism with the lowering movement of the upper die for stripping the pressed soap from the walls of the upper die, and provision is also made for rotating the lower die and causing the bar of pressed soap reposing therein to be ejected onto a conveyor belt. These mechanisms will be described in the order of their mention above.

A flywheel and die operating rotary element 107 is secured to the end of the main power shaft 23 on the opposite side of the machine from the driving pulley.

A bell crank lever 108 is mounted on a pivot rod 109 secured between bearing standards 110 formed integral with the main frame and extending upwardly at each side of the upper end thereof. One arm 111 of the bell crank lever extends rearwardly and has the upper end of a rod 112 secured thereto, security of the rod being by means of a pivot pin 113^a and a yoke element 113 adjustably mounted on the end of the rod. The lower end 112 of the rod is pivotally attached in a like manner to the flywheel toward the outer periphery thereof on a pivot pin 114. The connection of the rod to the flywheel is therefore eccentric and rotation of the flywheel imparts reciprocation to the rod and consequent swinging of the bell crank lever on its pivot. The fly-wheel is provided with radially disposed bores 115 in its periphery to permit hand rotation of the flywheel by means of a rod inserted therein in testing the machine.

The forwardly extending arm 116 of the bell crank lever is connected to the upper end of a swinging toggle link 117 which has its lower end pivoted to the upper die frame 118. The die frame 118 is in the nature of a slide suitably guided for vertical reciprocation within a dovetailed guideway 119 formed in the front upper wall of the frame.

Extending downwardly from the slide portion 120 of the die carrier or frame is a hollow rectangular portion 121 bifurcated or yoke-like at its upper end and having the upper die, oval in shape, secured to its lower end. The upper bifurcated portion has the lower end of the link 117 secured therein by means of a cross pin 122 rotatable in the respective sides of the bifurcated portion and secured to the link by means of a screw 123.

Incorporated in the link is a spring 124 suitably mounted to provide for a bringing together of the dies under spring pressure providing resilient engagement. The link provides side wall portions 125 joined by a cross wall 126 at the lower end and an intermediate cross wall 127. The side walls extend upwardly to provide a bifurcated or yoke end 128 for the link.

A headed rod 129 having the before mentioned cross pin of the die carrier traversing the head thereof is slideably mounted through the respective cross walls 126, 127. A collar 130 is disposed on the screw-threaded rod intermediate of the cross walls and toward the lower thereof, and the coil spring 124 surrounding the rod is under compression between the collar 130 and the intermediate cross wall 127.

A nut 131 screwed onto the upper end of the rod and against the upper face of the upper cross wall governs the relation of the die carrier to the link and is therefore adjusted to cause the dies to properly mate as they are brought together. The upper die may be set by adjusting the nut to compress the spring any desired amount or to permit a variable flexible mating of the dies over a considerable swing of the toggle. (See later description for the action of the toggle.) The spring engaged collar 130 is adjusted for the purpose of varying the compression of the spring, being formed for adjustment by means of a spanner wrench. The lower end of the die carrying slide is hollow as at 132 as a clearance for operation of a stripping mechanism hereinafter described. The slide portion of the die frame is open centrally as at 133 for clearance in the movement of the swinging yoke and a cross portion 134 joins the upper end thereof. A gib plate 135 removably mounts the the slide.

Adjacent the cam 83 a stripper mechanism operating cam 136 is mounted on the shaft 66. A bell crank lever 137 is pivotally mounted on the side of the frame on a bracket 138 and has one arm 139 thereof provided with a roller engaging in the cam track 141 of the stripper cam 136. The cam is made in two sections as shown in Figure 16, one section 142 thereof being pinned to the shaft and the other section 143 having the cam groove therein, being rotatably adjustably mounted on the pinned hub 144 of the first section. The respective parts are secured to

gether by means of set screws 145 traversing concentric slots 146 in the pinned element and screwed into the cam-grooved element. This provides the necessary adjustment to delicately change the relation of cam groove and roller to vary the movement of the stripper mechanism operated thereby.

The other arm 147 of the bell crank lever 137 extends through the hollow frame and has the lower end of a link or rod 148 pivotally secured thereto. The upper end of the link is secured to one arm 149 of a second bell crank lever 150 pivoted to the frame on a bracket 151 and having its other arm 152 extending toward the lower end of the die frame.

The arm of the bell crank lever extending toward the die is provided with a finger 153 engageable with the stripper mechanism located within the die frame and the die through the open portion 132 in the hollow die frame.

The two-piece upper die 154, ovate in this instance, is secured to the lower end of the die carrier 118 by means of screws 155 extending through the lower wall 156 of the hollow rectangular portion thereof into the outer die element 157. The outer die element 157 is provided with a bore 158 ovate in this instance to correspond with the outline of the particular soap to be pressed, this bore terminating within the die, and a circular bore 159 concentric with the center of the die and extending through the top thereof.

The inner die element 160 is of the same outline as the opening in the die and has a shank 161 extending into the circular portion being thus slideably mounted within the outer die or shell. A slide rod 162 screwed into the shank of the stripper extends upwardly slideably through the respective upper and lower wall of the rectangular portion of the die carrier.

A collar 163 is secured on the slide rod 162 intermediate of the portion thereof traversing the rectangular opening of the carrier and a spring 165 is interposed under compression between the collar and the floor of the opening. The collar 163 is the means engageable by the finger 153 for depressing the inner die element 160, the foregoing die action being described in detail hereinafter.

The spring holds the inner die element in a seated position within the outer die or shell. An ejector plunger 166 for stripping the pressed soap from the concave forming walls of the inner die element is slideably mounted within said element. This ejector plunger is substantially of the same formation as the inner die element, being slideably mounted therein and spring urged downwardly by means of a coil spring 167 seated within a concentric cylindrical recess 168 within the upper part of the plunger and under com-

pression therein against the top wall of the opening receiving the plunger.

Downward movement of this element under the action of the spring is limited by means of a set screw 169 engaged into the side wall of the inner die element and engaging a vertical longitudinal slot 170 formed in the side wall of the plunger.

As will be fully outlined, the inner die element having its lower surface formed to the desired curvature to be given to the upper part of the soap and forming the soap in combination with the lower wall portion 171 of the bore of the outer die, is designed for stripping the side or band of the pressed soap from this engaged portion of the outer die bore whereas the plunger engaging the top area of the formed soap is designed to strip the soap from the inner die.

The lower die 172 is mounted on a rock shaft 173 journalled in the side walls 174 of the frame. The die is secured to the shaft by means of screws 175 traversing slots 176 in the shaft and being screwed into the underside of the die, the slots being disposed longitudinally of the shaft for the purpose of permitting adjustment of the lower die relative to the position of the upper die. The lower die, which is immovable vertically, may be described as stationary during the pressing operation. However, after the upper die has been drawn away the lower die is revolved or oscillated forwardly to eject the pressed soap.

To accomplish this oscillation the following arrangement is provided: A cam 177 is mounted on the main power shaft 23 between the frame 20 and the driving pulley 25. A bell crank lever 178 is pivoted on a stud 179 extending from the side of the frame and one arm 180 thereof has a roller 181 engaging the cam groove 182. The other arm 183 extends upwardly and has one end of a rod 184 pivotally attached thereto, the other end of the rod 184 being pivotally connected to one arm 185 of a second bell crank lever 186 pinned to the outer extending end of the rock shaft. The cam groove is designed to impart rotation to the rock shaft sufficient to revolve the lower die from a directly vertical position forwardly a sufficient number of degrees to eject the soap.

The loose arm 187 of the bell crank lever pinned to the rock shaft serves as a swinging abutment designed to engage a stop element 188 secured to the side wall of the frame in such a position as to positively stop the reverse rotation of the rock shaft with the lower die disposed in accurate perpendicular position.

The lower die is provided with a stripper mechanism of the following nature: A plunger 189 having a flange 190 at its lower end is slideably mounted in the central bore

of the lower die, the flange moving in a lower counterbored portion 191. Normally, this plunger rests by gravity on the top of the shaft in a lower position with its top surface flush with the concavity of the lower die and forming the central area of the forming surface.

An operating means or slide rod 192 for the stripper plunger is secured concentrically 10 into the base side thereof and extends slideably through the shaft 173. The lower or extending end of the rod 192 is bifurcated and carries a roller 193. A cross pin 194 traversing the rod within the shaft engages diametrically opposite slots 195 in the shaft to prevent rotation of the rod for maintaining the roller in a fixed position. This pin functions 15 when the stripper is round.

In order to actuate the stripper plunger 20 189, a cam or dog 196 is secured to a cross rod 197 (see Figure 11) extending parallel to the rock shaft and secured in the respective side walls 174 of the frame, this rod being held in rotative adjustable position by means 25 of a segmental plate 198 secured to an outer end of the rod and having a slot 199 in its outer end concentric with the rod, this slot being traversed by a screw 200 engaged into the frame. The cam 196 is set in position to 30 be engaged by the roller upon rotation of the tumbler shaft in such wise as to move the plunger for ejecting the soap.

The face of the lower die in combination 35 with the top surface of the plunger forms the die surface for forming the lower face of the soap, a groove 201 being formed in the die surface marginally of its plunger bore. The upper inner die element has its die surface configurated precisely the same as the lower die. The side surface or band 202 of the soap is formed by the extreme lower end 40 171 of the upper die bore.

The operation of the dies is as follows: As 45 the upper die carrier 118 is moved downwardly, the finger 153 for actuating the inner die element for stripping the soap is swung downwardly in synchronism therewith, the strokes overlapping and the finger entering the rectangular opening in the carrier. The 50 upper die engages the lower, the finger stopping slightly above the collar, and the cylindrical bar of soap reposing in the lower die is pressed between the dies with the various stripper elements seated; the lower die plunger seating by gravity, the upper plunger depressed against the light spring 167, the inner die element 160 held in position by the spring 165. As shown in Figure 8, the upper 55 die twice exerts a pressing action on the soap. This is due to the swinging of the upper end 60 of the toggle link 117 past dead center into the position shown in dot and dash lines, the soap pressing actions occurring as the upper pivot of the link passes dead center. The 65 swinging of the toggle past dead center is

accomplished by the relation of the pivotal attachment of the rod 112 to the flywheel the dead center of which is considerably past the dead center of the toggle.

As the mechanism assumes the position shown in Figure 8 at dead center, the dies are forcibly engaged, the heavy spring 124 being compressed and the soap is pressed under spring action. Swinging past dead center to a position indicated in dot and dash lines, Figure 8, the compression of the spring is entirely relieved and the upper die carrier is slightly raised from the pressed soap.

As shown in Figure 9, the stripper plunger in the upper die being spring actuated forces 30 the soap to repose in the lower die during this slight raising movement of the upper die, the elements of the upper die raising as a unit.

Upon continued movement of the mechanism the bell crank lever 108 reverses and again approaches dead center or the position shown in Figure 8 and the soap is again pressed under the same pressure as in the previous instance. This double pressing of 35 the soap results in a permanent formation, the finished product having a definite sharp outline and a smooth finish.

The coil spring 124 is adjusted and the die carrier is adjusted on the toggle link to provide a degree of spring pressure and forcible mating of the dies to properly press the soap, depending on the degree of pliability of the substance.

The inner die element actuating finger 153 moved in unison with the downward movement of the die carrier has assumed a position, due to the shape of its operating cam, relative to the main stripper collar which it is designed to engage so as not to be engaged by said collar in the swinging of the link past dead center. However, as the bell crank lever 108 passes dead center the second time and is returning the die carrier to upper position, the collar is brought into engagement with the finger and the inner die element strips the soap from the walls of the die bore. The die shell is moved upwardly relative to the position of the inner die shown in Figure 9, and the result is to strip the outer die or shell bore engagement with the band of the soap.

The adhesion of the pressed soap to the stripper plunger then left engaging the top area thereof when the finger 153 moves away 120 from the collar 163 will not cause the soap to stick to the plunger because of the relatively smaller area of the top surface of the soap engaged as compared with the entirely engaged underside of the soap. As the upper 125 die thus moves away from the soap being stripped therefrom without raising the soap from the lower die, the stripper finger also moves away in synchronism therewith and returns to the position shown in Figure 7.

After the upper die has been drawn up, the rock shaft 173 is rotated by the previously described mechanism and the lower die 172 is revolved forwardly. The roller 193 incorporated as a part of the lower die stripper plunger 189 is revolved into engagement with the cam or dog 196 and ejects the soap from the lower die, the action of the plunger being such that the soap is stripped from the lower die curved portion and the stripper plunger due to initial impetus throws the soap from engagement therewith.

It will be readily understood that should it be desired to press the soap under a continuous pressure, even when the bell crank lever is completely back in its overthrow, this may be taken care of by adjusting the spring or varying the weight of the spring and adjusting the upper die carrier relative to the link. The action thus imparted would be somewhat of this nature: Pressure exerted would be very high at the time that the toggle mechanism was on dead center but as the overthrow took place there would be no raising of the lower die but the compression spring would relax and the pressure exerted would decrease accordingly with the spring taking-up or compensation for the overthrow, the dies always being engaged.

An endless conveyor belt 203 is provided toward the front of the machine for receiving and carrying away the discharged formed soap. The conveyor driving shaft 85 is suitably journaled in the brackets 41, 67, at the side of the frame and a sprocket gear 204 is pinned thereto, this sprocket being driven by means of a sprocket chain 205 from a second sprocket gear 206 secured to the power shaft 66. An idler roller 207 is adjustably mounted on a standard 208 bolted to the frame, the stub shaft 209 for the roller being secured in a slot in the bracket for moving the roller toward and from the chain. A pulley 210 is mounted on the forward extending end of the conveyor driving shaft and the conveyor belt is engaged thereabout.

Directly forward of the soap forming point stationary side rails 211 for the conveyor are provided supported on standards and extending from that point toward the opposite end of the machine from the driving pulley. These rails are suitably padded as at 212 at the soap receiving point so as to prevent any injury to the pressed soap discharged onto the conveyor at this point.

Having described my invention, I claim:

1. In a machine for successively pressing bars of pliable material, a magazine supporting a stack of said bars, carrier means for transporting the lowermost bar of the stack from the magazine, a pair of dies disposed transverse to the path of movement of said carrier means, one die reciprocable toward and from the other die, said latter die mounted for oscillation transverse to the pressing movement to eject the pressed article.

movement of the reciprocable die for ejecting the pressed article, and a conveyor moving laterally away from the forward side of the dies.

2. In a machine for successively pressing bars of pliable material, a magazine supporting a stack of said bars, ejector and carrier means for transporting successive bars from the magazine, a pair of dies, upper and lower respectively, disposed transverse to the path of movement of said ejector and carrier means, said upper die reciprocable toward and from the lower die, and said lower die mounted for oscillation transverse to the pressing movement of the upper die for ejecting the pressed article.

3. In a machine for successively pressing bars of pliable material, a magazine supporting a stack of said bars, ejector and carrier means for feeding the lowermost bar from the magazine, a pair of dies, upper and lower respectively, disposed transverse to the path of movement of said ejector and carrier means, said upper die reciprocable toward and from the lower die, said lower die mounted for oscillation transverse to the pressing movement of the upper die, die stripper elements mounted in the respective dies, and means for reciprocating said elements relative to said dies.

4. In a machine for successively pressing bars of pliable material, carrier means for feeding a bar, a pair of dies, upper and lower respectively, disposed transverse to and at each side of the path of movement of said carrier means, said upper die reciprocable toward and from the lower die, said lower die mounted for oscillation transverse to the movement of the upper die to eject the pressed bar, and a conveyor moving laterally away from the lower die forward side.

5. In a machine for successively pressing bars of pliable material, carrier means for feeding a bar, a pair of dies disposed transverse to the path of movement of said carrier means, one of said dies reciprocable toward and from the other die, and said latter die mounted for oscillation transverse to the pressing movement of the first die to eject the pressed bar.

6. In a machine for successively pressing bars of pliable material, a magazine for supporting a stack of said bars, ejector and carrier means for feeding the lowermost bar from the magazine, a pair of dies, upper and lower respectively, disposed transverse to the path of movement of said ejector and carrier means, said upper die reciprocable toward and from the lower die, said lower die mounted for movement laterally of the pressing movement to eject the pressed article.

7. A die construction, comprising, a pair of dies, one thereof comprising, a die shell slidably mounted for reciprocation relative to the other, an inner die element slidably

mounted in said shell, the combination of the inner bore wall of said shell and the lower face of the inner die element forming the die pressing area, an ejector plunger compressibly mounted in said inner die element, and a lever adapted to be interposed in the path of movement of the inner die element for interrupting movement thereof whereby relative movement of the shell strips the article being pressed from the bore wall of the shell and the ejector plunger strips the article from the walls of the inner die element.

8. A pressing means, comprising, a die immovably mounted in pressing movement, a die shell reciprocable relative to the first die, an inner die element slideably mounted in said shell, and a lever adapted to be interposed in the path of movement of the inner die element for interrupting movement thereof, whereby relative movement of the shell strips the article being pressed from the shell.

9. A die stripping means, comprising, a slideably mounted reciprocable die shell, an inner die element slidably mounted in said shell, a spring actuated ejector plunger mounted in said inner die element, and a lever adapted to be interposed in the path of movement of the inner die element for interrupting movement thereof whereby relative movement of the shell strips the article being pressed from the bore wall of the shell and the spring actuated ejector plunger strips the article from the walls of the inner die element.

10. In a device of the class described, a slideably mounted reciprocable die frame, an inner die element slideably mounted in said frame, the combination of the inner bore wall of said frame and the lower face of the inner die element providing a forming area, means for actuating said inner die element to strip the article being pressed from the bore wall of the frame, and a spring actuated plunger mounted in said inner die element for breaking the formed article from the walls of the inner die element.

11. In a device of the class described, comprising, a frame, a lower die mounted therein, an upper die slideably mounted in said frame for reciprocation relative to said lower die, a toggle mechanism for actuating said upper die, the link of said toggle being compressible during die engagement, and the swinging toggle lever and link connection movable past the dead center line of die reciprocation whereby a double die pressing action is imparted in forward and reverse movements of the toggle.

12. A device of the class described, comprising, a frame, a lower die mounted therein, an upper die slideably mounted in said frame for reciprocation relative to said lower die, a swinging lever pivotally mounted on said frame, a rod pivotally connected to said upper

die, a link connected to the end of said lever, said link having cross walls traversed by said rod, a collar on the rod engaging the upper surface of the upper cross wall, an adjustable collar on the rod intermediate the cross walls, and a spring under compression between the adjustable collar and the upper cross wall.

13. In a device of the class described, a frame, a lower die mounted therein, an upper die slideably mounted in said frame for reciprocation relative to said lower die, a toggle mechanism for actuating said upper die, the intermediate link of said toggle, comprising, relatively longitudinally slideable members, and a spring interposed therebetween for rendering the link compressible during die engagement.

14. A die pressing mechanism, comprising, a frame, a lower die mounted therein, an upper die slideably mounted in said frame for reciprocation relative to said lower die, a toggle mechanism for actuating said upper die, the intermediate link of said toggle, comprising, relatively longitudinally slideable members, and a spring interposed therebetween for rendering the link extensible during die engagement, and the swinging toggle lever and link connection movable past the dead center line of die reciprocation whereby a double die pressing action is imparted in forward and reverse movements of the toggle.

15. In a machine of the class described, a frame, an upper die and a lower die, the upper die journaled in said frame for reciprocation toward and from the lower die, the lower die mounted in said frame for movement laterally of the upper die, and ejecting means in said lower die operative by said lateral movement to eject the pressed article.

16. A device for pressing bars of pliable material, comprising, a lower die, a reciprocable upper die, said upper die comprising, an outer shell, an inner die element, a swinging finger moving in a path intersecting the reciprocable movement of the upper die and adapted to be positioned for engagement by said inner die element, means for reciprocating the upper die relative to the lower die, and means for positioning the finger for interrupting movement of the inner die element to strip the pressed article from the upper die.

17. A device for pressing bars of pliable material, comprising, a revolvably mounted lower die, an upper die reciprocable relative to the lower die, said upper die comprising, an outer shell, an inner die element, a swinging finger moving in a path intersecting the reciprocable movement of the upper die and adapted to be positioned for engagement by said inner die element, means for reciprocating the upper die relative to the lower die, means for positioning the finger for interrupting movement of the inner die element.

to strip the pressed article from the upper die, and means for revolving said lower die to eject the pressed article therefrom.

18. In a machine of the class described, a frame, an upper die and a lower die, the upper die journalled in said frame for reciprocation toward and from the lower die, and the lower die revolvably mounted for movement transverse to the line of die pressing movement.

19. In a machine of the class described, a frame, an upper die and a lower die, the upper die journalled in said frame for reciprocation toward and from the lower die, a rock shaft, means for rocking said shaft, the lower die fixed to said rock shaft, said shaft journalled for revolution of the die transverse to the line of upper die movement, and stripper plunger in both dies operated by the respective die movements.

20. In a machine of the class described, a frame, an upper die and a lower die, the upper die journalled in said frame for reciprocation toward and from the lower die, the lower die revolvably mounted for movement transverse to the line of upper die movement, and an ejector in said lower die operated by revolution of said die.

21. In a machine of the class described, a frame, an upper die and a lower die, the upper die journalled for reciprocation toward and from the lower die, and the lower die immovable in die pressing movement and journalled in the frame for revolution transverse of the line of die pressing movement.

22. In a device for pressing soap, a frame, an upper die and a lower die, the upper die journalled in said frame for reciprocation toward and from the lower die, the lower die fixed to a rotatable shaft for revolution of the die transverse to the line of upper die movement, an ejector plunger mounted in said lower die, and a cam faced abutment formed on said frame engageable by said plunger for operating the same when the die is revolved.

23. A machine of the class described, comprising, a magazine for supporting blocks of material in stacked relation, a reciprocating ejector moving across the base end of the magazine for ejecting the lowermost block, a reciprocating carrier moving in alignment with the ejector and depressibly engaging the opposite end of said block, and means for moving the ejector and carrier in spaced relation after engagement with the block.

24. A machine of the class described, comprising, a magazine for blocks of crude pliable material arranged in stacked relation, a reciprocating ejector moving transverse of the base end of the magazine for ejecting the lowermost block, a reciprocating carrier for engaging the opposite end of said block, toothed ends on said ejector and carrier for frictional engagement with the respective ends of the block, and means for moving the

ejector and carrier in spaced relation after engagement with the block.

25. A machine of the class described, comprising, a magazine for blocks of material disposed therein in stacked relation, reciprocating ejecting and carrier elements moving transverse to the base end of the magazine for feeding the lowermost block, laterally from the magazine, means on said ejector and conveyor for frictionally engaging the respective ends of the block, and means for moving the ejecting and carrying elements in spaced relation in engagement with the block.

26. A machine of the class described, comprising, a magazine for supporting cakes of material in stacked relation, a pair of aligned slides moving transverse to the base end of the magazine for ejecting and carrying the lowermost cake, said slides engaging said cake from opposite sides, and means for moving the ejector and conveyor in spaced relation after engagement with the block.

27. A machine of the class described, comprising, a magazine for supporting elongated blocks of material in parallel stacked relation, a reciprocating ejector moving transverse through the base end of the magazine and longitudinally of the blocks for ejecting the lowermost block, a reciprocating carrier element moving parallel to said ejector and engaging the opposite end of said block, means for moving the ejector and carrier in spaced relation in engagement with the block, and a pair of forming dies operating from each side of and transverse to the path of movement of the ejector and carrier.

28. In a machine of the class described, a frame, an upper die and a lower die, the upper die journalled in said frame for reciprocation toward and from the lower die, the lower die revolvably mounted in said frame, an ejector in said lower die operated by revolution of said die, and a stop for aligning said revolvable die for mating alignment with the upper die.

29. A mechanism for pressing pliable material, comprising, a pair of co-acting dies, upper and lower respectively, a frame, said upper die slideably mounted in said frame, toggle means for reciprocating said upper die toward and from the lower die, said toggle comprising, an operating lever and a compressible link between said lever and said slideable die, a stripping mechanism within said upper die, a lever for operating said stripping mechanism, said lever adapted to be positioned for engagement by the stripper mechanism in the first phase of return movement of the upper die, said lower die mounted in the frame for oscillation in a line transverse to the slide movement of the upper die, an ejector plunger in said lower die, and an abutment on said frame engageable by said

plunger when the die is revolved for moving the plunger.

30. A mechanism for pressing pliable material, comprising, a pair of dies, upper and lower respectively, a frame, said upper die slideably mounted in said frame, toggle means for reciprocating said upper die toward and from the lower die, said toggle comprising, an operating lever and a compressible link between said lever and said slideable die, a stripping mechanism within said upper die, a lever for operating said stripping mechanism, said lever adapted to be positioned for engagement between the stripping mechanism in the first phase of return movement of the die, and said lower die mounted in the frame and immovable in direction of pressing movement.

31. In a device for pressing soap, a frame, an upper die and a lower die, the upper die journaled in said frame for reciprocation toward and from the lower die, the lower die fixed to a rotatable shaft for revolution of the die transverse to the line of upper die movement, and means for ejecting the pressed article from the die, said means operated by die revolution.

32. A mechanism for pressing pliable material, comprising, a pair of co-acting dies, upper and lower respectively, a frame, said upper die slideably mounted in said frame, toggle means for reciprocating said upper die toward and from the lower die, said toggle comprising, an operating lever, and a compressible link between said lever and said slideable die, said lower die mounted in the frame and immovable in direction of pressing movement.

33. A mechanism for pressing pliable material, comprising, a pair of co-acting dies, upper and lower respectively, a frame, said upper die slideably mounted in said frame, toggle means for reciprocating said upper die toward and from the lower die, said toggle comprising, an operating lever; and a link between said lever and said slideable die, said lower die mounted in the frame for revolution in a line transverse to the pressing movement of the upper die, an ejector plunger in said lower die, and an abutment on said frame engageable by said plunger upon revolution of the lower die for an ejector movement of the plunger.

34. A mechanism for pressing pliable material, comprising, a pair of co-acting dies, upper and lower respectively, a frame, said upper die slideably mounted in said frame, means for reciprocating said upper die toward and from said lower die, stripping mechanism within said upper die, a lever for operating said stripping mechanism, said lever adapted to be positioned for engagement by the stripper mechanism in the first phase of return movement of the upper die, and said lower die mounted in the frame for

oscillation to eject the pressed article after retraction and stripping of the upper die.

35. A device for pressing soap, comprising, a stationary lower die, a reciprocable upper die, said upper die comprising, an outer shell, an inner die element, and a downwardly spring-urged ejector plunger in said inner die element, a swinging lever adapted to be positioned for engagement with said inner die element, means for reciprocating the upper die relative to the lower die, and means for cooperatively positioning the lever for permitting movement of the shell relative to the inner die element to strip the article pressed between the dies as the upper die is being retracted.

36. A device for pressing soap, comprising, a stationary lower die, a reciprocable upper die, said upper die comprising, an outer shell, an inner die element, a lever adapted to be positioned for engagement by said inner die element, means for reciprocating the upper die relative to the lower die, and means for cooperatively positioning the lever for permitting movement of the shell relative to the inner die element to strip the pressed article from the upper die in the first phase of upper die retraction.

37. In a machine for successively pressing bars of plastic material, a magazine supporting a stack of said bars, carrier means for transporting the lowermost bar of the stack from the magazine, a pair of dies disposed transverse to the path of movement of said carrier means, one die reciprocable toward and from the other die, and said latter die mounted for oscillation transverse to the pressing movement of the reciprocable die for ejecting the pressed article.

38. In a device of the class described, a frame, a pair of dies mounted therein, one of said dies mounted for reciprocation relative to the other die, a toggle mechanism for actuating said reciprocable die, the intermediate link of said toggle comprising relatively longitudinally slideable elements, and a spring inserted between said elements for rendering the link compressible during die engagement.

39. In a machine of the class described, a frame, a pair of co-acting dies mounted therein, one of said dies journaled in said frame for reciprocation toward and from the other die, the other die mounted in said frame for movement laterally of the reciprocable die, and plunger means in said laterally movable die operative by said lateral movement to eject the pressed article.

40. In a machine of the class described, a frame, a pair of co-acting dies mounted therein, one of said dies journaled for reciprocation toward and from the other die, a rock shaft mounted in the frame, means for rocking said shaft, said other die fixed

to said shaft, said shaft disposed for rocking said other die transverse to the line of die pressing movement, and stripper plungers in both dies operated by the respective die movements.

⁵ In witness whereof, I hereunto subscribe my name.

RUEL ANDERSON JONES.
